CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

EMBOSSING AND PRINTING MACHINE.

Application filed October 27, 1924. Serial No. 745,968.

My pending application No. 535,311 filed February 9, 1922, illustrates an embossing machine where there is a longitudinally reciprocable die-carrier having male and female dies, a keyboard for moving and positioning the die carrier and mechanism operating automatically, consequent upon the die carrier coming to position, to plunge positioned dies toward each other, to emboss an interposed strip of metal.

The present invention relates to a very simple mechanism adapted to be coupled with such an embossing machine for printing the characters on a continuous strip of paper as they are embossed on the strip of metal, the printed characters being readily visible to the operator. The printed strip thus forms a visible indication to the operator as to whether the proper keys have been struck.

By a very simple arrangement of a scale adjacent the paper strip I am able to indicate to the operator just where he should cut off the embossed strip for the proper length of line. I provide means for automatically placing a distinctive mark on the paper strip whenever the shearing key of the embossing machine is operated, whereby the successive lines on the paper strip are visually separated though they are all in a continuous row.

The present invention includes the printing and indicating mechanism above outlined. It also includes a shift mechanism cooperating with the printing mechanism, enabling the selection of a desired row of printing characters from a plurality thereof on the wheel which effects the printing. It also includes simple devices for effecting the inking of the printing wheel, and for accurately centering the printing wheel to prevent vibration thereof and insure an accurate imprint.

The above and other features of the invention will be apparent from the following detailed description of a preferred embodiment illustrated in the drawings.

In the drawings, Fig. 1 is a side elevation of an embossing machine coupled with my printing mechanism; Fig. 2 is a plan of the printing mechanism and die carrier and di-

rectly associated parts; Fig. 3 is a longitudinal vertical section through the machine on the plane indicated by the offset line 3—3 on Fig. 2; Fig. 4 is a vertical section on the line 4—4 of Fig. 1; Fig. 5 is a fragmentary view 55 of the printed paper strip, illustrating the manner in which the end of the line is indicated; Fig. 6 is a vertical section through the printing wheel and one of the inking rollers, as indicated by the line 6—6 in Fig. 2; Fig. 7 60 is a detail of the scale and pointer, being a vertical section on the line 7—7 on Fig. 4; Fig. 8 is a transverse vertical section through the die-carrier as indicated by the line 8—8 on Fig. 1; Fig. 9 is a detail illustrating the 65 guide rolls for the paper strip, being a vertical section on the line 9—9 on Fig. 2; Fig. 10 is a plan of the shift keys and their lever, shown in elevation at the right hand end of Fig. 1; Fig. 11 is an elevation of the same 70 mechanism, in different position from that shown in Fig. 1; Fig. 12 is an elevation illustrating the shift keys as they are returning to normal position; Fig. 13 is a sectional detail of the shift keys and vertical section 75 on the line 13—13 in Fig. 10.

I will first describe the embossing machine shown, it being understood that a complete keyboard is provided, having the usual alphabetical, numerical and punctuation characters, and mechanism controlled by the actuation of any key for correspondingly positioning the die carrier.

Figs. 1, 2, 3 and 8 show the die carrier, which is a reciprocable block 10 having a 85 longitudinal opening or channel 11 in its upper portion. This block is guided to reciprocate on rods 12 and 13. Lying within the channel 11 is a pair of frame rails 20 and 21. The die-carrier has a pair of rolls 15 and 16 bearing on opposite sides of these rails. The lower end of the rail 21 is provided with a longitudinal rib 22 forming a support and guide for the channel-shaped metal strip "A" being embossed. This strip is periodically progressed from left to right by a pair of rolls 25 and 26 actuated by a ratchet wheel 27 and pawl 28 connected with the embossed mechanism as hereinafter described.

The die-carrier carries a row of male die blocks 30 and a corresponding row of female die blocks 31. Such blocks face each other and are adapted to be plunged toward each other to emboss the interposed strip. As shown each die block carries in a vertical row, three related faces, as for instance, lower face, upper face and numerals or punctuation marks. The dies are normally retained in their inactive position by springs 33 carried by suitable brackets 32 rising from the die carrier. Suitable shift mechanism, hereinafter described, raises the carrier from the normal position shown in Fig. 1 to bring either of the other die faces into the horizontal plane on the metal strip "A."

The mechanism illustrated for moving the die carrier comprises a pair of solenoids 35, (Fig. 2) operating on a common core bar 36 connected by a link 37 with a pivoted arm 38, the pivot being beyond the illustration in Fig. 2. The other or forward end of this lever 38 is bifurcated, as at 39, and embraces a block 34 pivoted to the underside of the die carrier. Suitable means, not shown, are provided for enabling the depression of any key on the right-hand half of the key-board to energize the left-hand solenoid 35, thereby drawing the die carrier toward the left to bring into central position the corresponding pair of dies in the right-hand half of the die carrier. Similar action of any key on the left-hand half of the key-board results in the die carrier movement toward the right to position a corresponding pair of dies in the left-hand half of the die carrier.

Immediately upon the die carrier coming to central position, suitable clutch mechanism, not shown, is automatically thrown into action causing a single rotation of the shaft 50 (Fig. 1). This shaft carries a pair of double crowned cams 51 and 52 which operate levers 53 and 54, which carry at their upper ends adjustable studs 55 which serve to push toward each other the reciprocable plungers 56. These plungers thus engage the pair of dies which are in central position and force them toward each other to emboss the interposed strip.

Some of the keys of the keyboard are indicated at 40, in Fig. 3. These keys have levers 41 extending rearwardly and intermediately pivoted, as at 42. The rear ends of the key levers stand alongside of each other, as shown in Fig. 8, and are guided by vertical slots in a transverse frame member 14. The die carrier has a suitable latch mechanism adapted to coact with the raised rear end of any key lever to lock the carrier with the dies corresponding to such key in active position. The latch mechanism shown in Figs. 3 and 8 comprises a pair of vertical plungers 45 having beveled lower ends 46, and suitable L-shaped abutments 47 constrained by springs 48.

When the die head is released by the depression of a key, the solenoid which is energized by such depression causes the head to move toward the rear end of that key lever until stopped by the abutment 47 engaging such key lever. Just before this takes place, the plunger 45 will be cammed upwardly by its beveled bottom engaging the key lever and will then drop down on the far side of the lever, thereby locking the die head to the key lever. Fig. 8 shows one of the plungers as it is traveling over the raised key lever end 44 and just before the die head comes to a stop.

The abutments 47 and plungers 45 are mounted in a suitable housing 17 which travels laterally with the die head, and is guided by a roller 18 in a channel in a frame member 19. The die head is vertically slideable with reference to the housing to select different faces on the die blocks as herein-after explained, but for lateral movement the two operate as a unit.

Resting on the upper ends of the plungers 45 is a pivoted ball 49 which is connected by a link 57 with a bell crank 58 connected to a rod 59 which controls the clutch mechanism above mentioned. Accordingly, just as the die head is coming to position, the raising of the corresponding plunger 45 causes a withdrawal of the rod 59 releasing the clutch to effect the single rotation of the shaft 50 to cause the embossing action of the dies as already described.

To enable an embossed line to be readily cut off from the unembossed portion of the strip, I provide in the die head, a pair of shearing dies 23 and 24. These dies are preferably male and female and may have the form shown, in plan, on dotted lines in Fig. 2 and in elevation in full lines in Fig. 3. I provide in the keyboard a special key 43 which operates to position these dies in alignment with the die-operating plungers. It is the rear end of the key lever 44 on this key which is shown in elevated position in Fig. 8. When the die carrier is stopped by such key, the shearing dies 23 and 24 are in line with the reciprocable plungers 56. The operation of these dies therefore is similar to that of character dies except that the strip is sheared in two instead of embossed. While the character dies preferably have multiple faces, I prefer to provide only a single pair of shearing dies located in the row of lower case characters.

The printing mechanism operates concurrently with the embosser, printing a character on a paper tape whenever a character key is struck, and printing a suitable mark on the tape to indicate the end of a line, whenever the shear key is operated. This printing mechanism includes a rotary printing wheel 60 (Figs. 1, 2, 3 and 6), which has rows of characters corresponding to the

rows of faces on the die blocks,—three rows being shown. This wheel is preferably cored or drilled for lightness as shown at 61 in Figs. 2 and 6, and is freely journaled 5 on a stationary vertical stud 62, shown as carried by a portion of the frame 63. Below the wheel proper is a reduced cylindrical extension 65 secured to the lower end of which is a gear 66. This gear meshes with 10 a rack 67 secured to the top of the die carrier 10. In Figs. 2 and 6 an arm 70 is shown pivoted at 71. This arm carries adjacent its end a roller 72 riding on the upper face of the rack, and carries also a roller 15 73 riding on the under face of the type wheel. Specifically this roller 73 bears against a washer 75 surrounding the type wheel shank as shown in Fig. 6.

It will be seen from the construction described 20 that when the die carrier is shifted longitudinally in either direction, the wheel is given a partial rotation correspondingly. When the die carrier is shifted vertically to change the "case" of the active 25 dies, the wheel is correspondingly shifted by reason of the floating rollers described. Accordingly, the proper character in the row of type, as well as the proper row, is brought into printing position, in correspondence 30 with the dies which are brought into the active position.

On opposite sides of the type wheel, I provide a pair of inked rollers, 80 which are preferably of absorbent material such as 35 felt and once inked will carry such ink for a suitable length of time. As shown in Fig. 6, the felt is in the form of a thick sleeve 80 mounted on a tubular core 81 on a head 82. The felt is compressed by a disc-like 40 nut 83 screwed onto the upper end of the tubular core. This compound spool is rotatable on a stud 85 carried by the frame member 63. The construction of the spool described enables the felt to be replaced 45 whenever desired by the simple removal of the disc nut 83. Moreover by screwing down this nut onto the felt, the latter is compressed and forced radially outward to compensate for wear caused by the printing 50 characters 64.

To cause the inking spools to shift vertically with the printing wheel, I make the heads 82 on the spools of greater diameter than the spools and extend them into a peripheral groove 88 in the printing wheel. As shown this groove is provided by the 55 washer 75 and a rabbitt in the bottom of the wheel proper. By this arrangement, any drag on the wheel across the felt and the 60 consequent foul of the type, is avoided.

The tape of paper to be printed, indicated at "B" in Figs. 1, 2, 4 and 9 is carried on a reel 90, (Fig. 2) rotatably mounted on a stationary stud 91. The paper tape 65 leads from this reel across the guide roller

93 and thence across a portion of the face of the platen roller 95 and thence behind a guide pin 96 and into a longitudinal guideway 97. This guide comprises a strip of metal with its edges flanged forwardly and downwardly, whereby an undercut passage-way is provided to guide the tape and still expose it, except at its edges. This guideway is somewhat longer than the longest line intended to be embossed by the machine. 75

At the left-hand end of the guideway 97 is a roller 100 around which the paper tape extends. The tape thence passes behind the guideway and into the grip of a suitable feed mechanism. As shown, I accomplish 80 the feed very simply by providing a roller 102 which bears against the platen roller 95 and is geared therewith by gears 103 and 104. The paper tape is gripped between these rolls and periodically fed by partial 85 rotations given to the platen roller described.

The platen roller 95 and the guide rollers 93, 100 and 102 and the longitudinal guideway 97 are all mounted on a rocking frame 90 110 which is pivoted at some suitable point as 111 and 112 to a part of the stationary frame. This rocking frame extends below the pivot 111 in the form of an arm 113 which is connected by a link 114 with an arm 115 secured to the hub of the embossing lever 53 on the shaft 119. From this it follows that when this embossed lever swings, to plunge forward the corresponding die to effect embossing, the rocking frame 110 is likewise swung forward (but to a less distance) to bring the paper tape 100 into engagement with the positioned printing character 64 on the type wheel. Suitable eccentric adjustment 118 between the 105 arm 113 and link 114 enables this movement of the paper tape against the type wheel to be adjusted to cause the desired depth of impression.

The roller 93 and the roller 100, each is 110 provided with a bottom flange for supporting the tape of paper. Roller 102 preferably has both top and bottom flanges to effectively confine the tape against the platen 115 roller.

Mounted on the platen roller 95 is a ratchet wheel 120. On the forward or printing stroke, this wheel clicks idly across the tooth of a pawl 121, but on the rearward stroke engagement of this pawl with a 120 ratchet tooth gives a rotation of the platen wheel sufficient to feed the paper a distance corresponding to the width of one character.

The feed described is caused by the coaction 125 of the platen roller 95 and the feed roller 102. This latter roller is mounted on an arm 125 pivoted at 126 and drawn toward the platen roller by a spring 127. The other end of this spring is anchored to an arm 128 which carries the idler roller 93. 130

An eccentric 129 mounted on the arm 128 and provided with a screw-driver slot by which it may be turned, furnishes an adjustable stop for the arm 28 whereby the idler 93 may be held in adjusted position with reference to the platen roller. This idler roller does not contact with the platen roller but by varying its proximity thereto, the extent of the periphery of the platen roller which the paper tape engages is varied and thus an adjustable tension is provided. This enables varied grades of paper to be kept taut in the guide 97.

The paper tape may be initially positioned by rotating the platen roller 95 and it has a geared roller 102. To enable this to be readily effected I pin the platen roller 95 to the pin 105 which is freely journaled in frame member 110 and the overhanging bracket portion 117 thereof, and I provide a knurled knob 107 in the upper end of the pin. This enables the platen roller to be turned mainly in the direction to feed the paper tape. If it be desired to backspace the paper tape, this is readily effected by the same means when the pawl 121 is swung away from the wheel 120. A suitable peg 124 projecting upwardly from this pawl enables it to be conveniently shoved aside by the operator's finger.

The types 64 on the printing wheel are preferably embossed on metal strips extending about the periphery of the wheel and anchored thereto in a notch in the wheel as indicated at 130 in Fig. 2 at one end and at the other by a pin 135. Associated with one of these printing strips is a member for printing a vertical line on the strip of paper. I have shown this member as a thin plate 132, secured to the type wheel by one of the screws 133 securing the lower case or top type strip 64. This plate 132 is so positioned on the type wheel that it comes into coaction with the platen whenever the die carrier is positioned to bring the shearing dies thereof into active position, and when such shearing dies are operated to cut off the finished portion of the embossed strip, and the platen frame is thus automatically swung forward, this printing member 132 prints a vertical line on the paper tape, as indicated at "b" in Figs. 4 and 5. This accordingly marks the end of the line.

It will be seen that while my machine prints the lines successively on a continuous tape of paper, the length of each line is indicated by means of the imprinted vertical line "b". This same arrangement enables the operator to gage the length of the embossed and sheared lines. To this end I provide a scale 140 carried by the rocking arm 110 directly over the strip guideway 97. This scale is guided into equal spaces corresponding to the width of the characters. Slidable longitudinally of the scale is a suit-

able pointer, preferably a spring metal clip 143, U-shaped as shown in Fig. 7, having bowed portions embracing the upper and lower edges of the scale and having a depending prong 144 directly adjacent to the upper edge of the paper strip.

Before the embossing operation, the operator sets the pointer at a distance from the right-hand end of the scale 140 corresponding to the length of the line to be embossed. Then, when the left-hand portion of the line on the tape reaches the pointer, the operator knows that his embossed line is of the desired length. Thereupon, he operates the shearing key to cut off the embossed line, and this results in printing the line indicator "b" on the strip, marking the end of that line. This tape may also be utilized, if desired, as a proof or record of the lines embossed.

To position accurately the die carrier and the printing wheel and lock them during the embossing and printing operation, I provide the locking device shown in Figs. 2 and 3, consisting of a rack 150 on the die carrier having beveled teeth and a plunger 152 carried by the frame and having at its forward end corresponding teeth 151. This plunger is freed from the die carrier during the positioning thereof, being held back by lugs 153 on the upper end of the embossing lever 54 which engage a cross head 155 adjustably clamped to the plunger 152. A pair of springs 157, anchored to this cross head to a stationary frame housing 158, tends to pull the plunger 152 forward, and effects this operation as soon as the plunger is released on the forward stroke of the embossing lever 54. Accordingly, before the embossing or printing takes place, the beveled teeth on the plunger 152 come into coaction with the beveled teeth 150, accurately centering and locking the die carrier and printing wheel.

The cross head 155, is adjusted on the plunger 152 by reason of the nut 158 and the clamping screw 159, Figs. 1 and 2. The active end of the plunger 152 is wide enough to engage the rack 150 on the die carrier irrespective of the vertical position of the latter, as controlled by the shift mechanism about to be described.

Referring to Figs. 1 and 2, the bar 12 on which the die carrier slides, is mounted at its ends in vertical shiftable blocks 160. These blocks have pins 162 occupying the bifurcated rear ends of a pair of shift levers 164 and 165. These levers are pivoted on pins carried by brackets, of which one is shown at 166, and two levers are connected by a cross-bridge 167. The lever 164 extends forwardly of the pivot and carries the shift keys and cooperates with the latch mechanism which I will now describe.

As shown in Figs. 1 and 10 to 13 inclusive, slidably mounted in the forward end of the

lever 164 is the shank 171 of a key 170. At the rear of this is a key 172 which is rigidly secured to the lever. Depending from the lever is an adjustable stop rod 174. The shank 171 of the key 170 has a limited sliding movement in the lever by reason of a pin 175 occupying a notch 176 in the shank. The lower end of this shank and also of the stop pin 174, are adapted to engage a stationary abutment 178 carried by the frame. 10

The parts described are normally in the position shown in Fig. 1, which corresponds to the upper row of characters in the die head and the printing wheel. Now, if the operator places his finger on the key 170 and presses it down until its lower end strikes against the abutment 178, he will thereby lower the shift lever one step, which raises the die carrier and type wheel to bring the second row of characters into action. If, on the other hand, the operator places a finger on the key 172 and forces the shift lever down to the limit, this limit will be provided by the pin 174 striking the abutment 178, the shank 171 sliding relatively upward in the shift lever. This lowers the forward end of the shift lever two steps, bringing the lowermost row of characters on the die carrier and the printing wheel 20 into action.

To hold the shift lever in either of its shifted positions, I provide a latch 180 having a pair of teeth 181 and 182 adapted to engage a lip 183 on the shift lever. A spring 185 anchored to the latch tends to swing it toward the lip 183. When the key 170 is depressed, as described, the tooth 181 accordingly comes over the lip and holds the parts in their intermediate position (shown 30 in Fig. 11); when the key 172 is depressed, the tooth 182 engages the lip and holds the die head and printing wheel in their uppermost position.

To return the die head and printing wheel 40 to normal or lower case position after each embossing operation, I provide the following described mechanism (which, however, may be thrown out of action to emboss any of the unusual cases for more than one character) namely, I mount on the shaft 195 of the embossing lever 54, an arm of lever 190 which is connected by a link 191 with a rocking arm 192 to which is pivotally connected a bar 193, the free end of which normally rests on a pin 194 on the side of a latch 180. The bar 193 carries a pin 196 overhanging the top of the lip 183. When one of the keys 170 or 172 is depressed, the latch 180 is cammed forwardly by the lip 183. This 50 carries the pin 194 from under the main portion of the bar 193 so that bar follows downwardly after the depression of the shift lever and thus its shoulder stands in front of the pin 194. Now, following the embossing operation, on the return of a lever 54, the lever

190 shoves forwardly the bar 193 and thus swings the latch bar 180 out of engagement with the lip 183 and thus the shift lever is free and the die head and type wheel drop by gravity to normal or lower case position. 70 As the forward end of the shift lever rises the pin 196 causes the bar 193 to be restored to normal position.

In case it is desired to cause the mechanism to remain in its shifted position for 75 more than a single character at a time, it is only necessary to swing backwardly the bar 193 on its pivot into the position shown in broken lines at 193^a in Fig. 11. Then the throw-out mechanism described is idle and 80 the die head and printing wheel remain in whatever shifted position has been given the shift key 170 or 172.

The upper end of the arm 190 is connected by a link 200 Fig. 2 (omitted in Fig. 85 1) with the rocking arm 201 carrying the pawl 28 coating with the strip feed ratchet 27 heretofore described. This results in the metal strip "A" being fed a distance corresponding to the width of each character 90 consequent upon the return of idle position of the embossing lever 54.

I claim:

1. The combination with embossing mechanism, of means for guiding and feeding a 95 ribbon of material to be embossed, means for holding a strip of paper, mechanism for printing successive characters thereon in the direction of the length of the strip including means for feeding the strip lengthwise, a 100 keyboard and mechanism actuated thereby for operating both the embossing mechanism and the printing mechanism, mechanism for severing the embossed portion of the ribbon, a group of words printed on the paper strip 105 corresponding to a single cutoff embossed strip, and each group of words corresponding to successive embossed strips aligning with the preceding printed group.

2. The combination with a series of dies 110 and means for carrying a ribbon of metal adapted to be embossed by said dies, and printing mechanism, a pair of rollers for engaging and feeding a ribbon of paper adapted to be printed by said printing mechanism, and a common keyboard for actuating the dies and the printing mechanism.

3. The combination of a series of dies, a shiftable die head carrying them, means for carrying a ribbon of metal between said dies, 120 a printing mechanism, a spool for carrying a ribbon of paper, means for feeding the paper from the spool a letter space for each character embossed, and a common keyboard for positioning the die head and printing mechanism and for actuating the dies and the printing mechanism.

4. The combination of a reciprocating die head, dies carried thereby adapted to effect embossing, a rotary printing wheel, mecha- 130

nism for correspondingly positioning die head and printing wheel, a platen coacting with the wheel, means for feeding a strip of paper between the wheel and platen, and a keyboard for actuating the dies and printing device.

5. The combination of means for carrying a ribbon of metal, a reciprocatory die head, dies carried thereby and located on opposite 10 sides of such ribbon of metal, a rotary printing wheel geared with the die head, means for carrying a strip of paper in position to coact with the printing wheel, a keyboard having finger keys, mechanism controlled thereby for simultaneously positioning the 15 die head and the printing wheel, and automatic means for operating the dies and printing device.

6. The combination with an embossing 20 mechanism, of mechanism for holding a strip of paper in the form of a roll, mechanism for printing thereon, and mechanism for feeding the strip in the direction of the line printed thereon and simultaneously 25 winding such strip from the roll, a keyboard and mechanism actuated thereby for operating both the embossing mechanism and the printing mechanism.

7. The combination with embossing mechanism of a printing wheel, a platen coacting therewith, a paper guide, means for feeding the strip of paper between the platen and printing wheel and along the paper guide, a keyboard and mechanism actuated thereby 30 for operating both the printing mechanism, and the embossing mechanism.

8. In a combined embossing and printing machine, the combination of a movable die head, individually operable dies carried 40 thereby, a rotary printing wheel geared with the die head, a keyboard for simultaneously positioning the printing wheel and die head, a platen for the printing wheel, mechanism for automatically moving the dies toward 45 each other and moving the platen into coaction with the printing wheel, means for guiding a strip of paper between the printing wheel and platen, and so supporting it that it is visible toward the operator of the 50 keyboard, for a distance at least as great as the length of a line, and means for periodically feeding said strip of paper in the direction of its length.

9. The combination with printing mechanism and a keyboard for operating it, of a guide for a strip of paper comprising a vertical plate with its edges curled toward each other on the front side and adapted to embrace the edges of a strip of paper while 55 exposing the intermediate portion to the view of the operator at the keyboard, and mechanism for feeding said strip of paper along such guide.

10. The combination with a printing 60 wheel adapted to be rotated, a platen, mech-

anism for moving the platen toward the printing wheel, means for guiding a strip of paper across the face of the platen and thence along a straight exposed region extending in a horizontal direction toward the 70 left of the printing point for a distance as great as the length of a line.

11. The combination of a printing wheel adapted to be rotated, a platen wheel, mechanism for causing the platen wheel and the 75 printing wheel to coact, a roller coacting with the platen wheel to feed a paper strip between them, and a paper guide exposing a region of a strip between the platen wheel and said roller.

12. The combination of a printing wheel, a platen wheel, means for swinging the platen wheel against the printing wheel, a feeding wheel coacting with the platen wheel, a paper guide interposed between the 85 printing point and the line of coaction of the platen wheel and feeding wheel, and means for guiding a strip of paper across the platen wheel and along said guide, and thence between such feeding wheel and platen wheel.

13. The combination of a printing wheel, a platen wheel, means for swinging the platen wheel against the printing wheel, a 95 paper guide, means for guiding a strip of paper across the platen wheel and along said guide, a return pulley at the far end of the guide about which the strip passes, and a feeding wheel coacting with the platen wheel, the paper strip then passing between 100 such feeding wheel and platen wheel.

14. In a machine of the character described, the combination of a rotary printing wheel, a platen in the form of a wheel, a swinging frame carrying such platen wheel, a roller coacting with the platen wheel and yieldingly forced toward the same, means for guiding a strip of paper along an exposed course at the left of the printing point and thence between the platen 105 wheel and roller, and means for periodically rotating said platen wheel and roller 110 to feed the strip step by step.

15. In a machine of the character described, the combination of a rotary printing wheel, a platen in the form of a wheel, a swinging frame carrying such platen wheel, a roller coacting with the platen wheel, means for guiding a strip of paper to be printed between the platen wheel and printing wheel, means for then exposing a region of said strip, means for then guiding said strip between the roller and platen wheel, and means for periodically rotating 115 said roller and platen wheel to feed the strip step by step.

16. The combination with a printing wheel, of a platen wheel adapted to act as a hammer therefore, means for guiding a strip of paper to be printed between the 120 125 130

- printing wheel and platen wheel and a flanged roller coacting with the platen wheel and serving to feed the strip of paper, the flange of the roller operating to support 5 said strip.
17. The combination of a rotary printing wheel, a platen coacting therewith, means for guiding and feeding a strip of paper in the direction of the printed line between the 10 printing wheel and platen, a stationary guide along which said strip may be fed for a distance as great as the length of the line, a scale located adjacent to said stationary guide, and a pointer cooperable 15 with said scale.
18. The combination of a rotary printing wheel, a platen coacting therewith, means for guiding and feeding a strip of paper in the direction of the printed line between the 20 printing wheel and platen, a stationary guide along which said strip may be fed in a straight line, a scale located parallel with and adjacent to said stationary guide, and a movable pointer shiftable along said 25 scale.
19. The combination with a printing wheel and platen, of a straight vertical guide adjacent thereto having flanged edges to guide a strip of paper with the intermediate region exposed, a scale extending 30 parallel with said guide, and a pointer movable relatively to the scale.
20. In a printing mechanism, the combination of a wheel, mechanism for rotating it, a platen adapted to coact therewith, a line of printing characters on the wheel, said characters being formed on strips separate from the wheel, said wheel having a recess on one portion in which the end of 40 a strip is anchored and a recess on the opposite side into which another portion of a strip may extend, and a pin occupying the latter recess to hold the printing strip in place on the wheel.
21. In a machine of the character described, the combination with means for simultaneously embossing and printing, of mechanism for cutting off the embossed strip and indicating such condition on the article 45 printed.
22. In a machine of the character described, the combination with means for simultaneously embossing and printing, of mechanism for simultaneously shearing the embossed strip and placing a mark on the article printed.
23. The combination of means for feeding a ribbon of metal, means for feeding a strip of paper, means for simultaneously 50 embossing the metal ribbon and printing on the paper strip, and means for simultaneously shearing the metal strip and forming an indication on the paper strip.
24. The combination with embossing 55 mechanism and printing mechanism, of
- means for feeding metal to be embossed and paper to be printed, a keyboard having keys for simultaneously effecting the embossing and printing, a shearing key for cutting off the embossed metal, and mechanism actuated thereby for placing a mark on the printed paper.
25. The combination of embossing dies, means for feeding a ribbon of metal between them, a printing mechanism, means for feeding a strip of paper through the printing mechanism, a keyboard having finger keys, mechanism operated thereby for simultaneously operating the dies to emboss the metal ribbon and the printing mechanism to print on the paper strip, means for cutting off the embossed portion of the metal ribbon, means for placing a mark on the printed strip, and a manual actuator for simultaneously actuating said last two means.
26. In a machine of the character described, the combination of a plurality of rows of characters, shift mechanism to bring different rows into active position, said shift mechanism including a lever having a pair of finger keys thereon, one of said keys being rigid with the lever, the other slidably mounted on it, and means for stopping the depression of the lever and for stopping the slideable key without stopping the lever whereby the lever may be depressed at different amounts.
27. In a machine of the character described, the combination of a rotary printing wheel having a plurality of rows of characters thereon, keyboard-controlling mechanism for rotating it to bring it into position, shift mechanism for moving it axially to bring different rows into active position, said shift mechanism including a lever having a pair of finger keys thereon, one of said keys being rigid with the lever, the other having its shanks slidably mounted in it, and means for stopping the depression of the lever and for stopping the slideable key without stopping the lever whereby the lever may be depressed different amounts.
28. The combination with a shiftable printing mechanism, of a shift key therefor, a detent device adapted to retain the shift key in shifted position, mechanism for automatically throwing said detent device out of action following each impression, and means whereby said throwout device may be moved to idle position.
29. The combination with a shiftable printing mechanism, of a shift key therefor, a latch adapted to retain the shift key in shifted position, a movable abutment mechanism for automatically moving it against the latch following each impression, said abutment being pivoted and adapted to be swung back to idle position.
30. The combination with a shiftable die head, a printing wheel geared therewith, key-

board-controlled mechanism for shifting the die head and printing wheel, mechanism for operating the dies to effect the embossing and the printing wheel to effect the printing, a center lock for accurately positioning the die head and printing wheel, a spring tending to actuate with the center lock, means for operating the dies, and means whereby the die-operating mechanism releases the center lock to enable the spring to set the lock.

In testimony whereof, I hereunto affix my signature.

CLIFTON CHISHOLM.
